GOLF BALL

Boris Bogoslovsky, New York, N. Y.

Application September 21, 1937, Serial No. 164,851

4 Claims. (Cl. 273—62)

This invention relates to golf balls and to methods of making the same.

It is an object of the invention to provide an improved ball and an improved method of making 5 the same.

In the manufacture of golf balls according to ordinary methods, it is usual to wind successive convolutions of rubber strand, usually in the form of thread or ribbon, under tension, around 10 a center or "pill" as it is generally called. These pills are of various types, as for example, solid rubber, or more commonly, a rubber sac filled with fluid. In winding the rubber strand around the pill, it is common to apply relatively high tension 15 to the rubber strand and to maintain this tension constant throughout the winding operation.

In my copending application, Serial No. 122,957, now Patent No. 2,153,408, I have described a golf 20 ball and method of making the same, in which no pill is used, the ball being formed by winding successive convolutions of rubber strand from the geometric center of the ball to the outer periphery thereof. In making balls in accordance 25 therewith, I have heretofore followed the common practice of applying relatively high tension to the rubber strand, and maintaining this tension constant throughout the winding operation.

I have now discovered that improved results 30 can be obtained, both in balls of the conventional type, wound around a pill, and in balls of the type of my previous invention, wound from the geometric center, by applying progressively increasing tension to the rubber strand as the 35 winding progresses.

There are various possibilities for combinations of windings at constant tension and windings at progressively increasing tension. For example, the initial windings, whether applied to a pill or 40 otherwise, may be applied at increasing tension, followed by subsequent windings at constant tension.

Certain of these possibilities are illustrated in the accompanying drawing, in which,

45 Figures 1 and 2, are cross sections through various types of balls embodying my invention.

In Figure 1, the ball is wound from its geometric center, the tension applied to the strand 4 increasing progressively from the center to any 50 desired intermediate point 5, where the maximum tension is reached, the maximum tension being maintained constant during the remainder of the winding. Thus the rubber strand of the ball is in a state of tension that progressively 55 increases from the center to the intermediate

point 5, and from the point 5 to the periphery or cover 7 is substantially uniform but greater than the maximum tension existing up to the point 5.

In Figure 2 the ball is wound on a pill 2 of any desired construction, the tension applied to the strand 4 increasing progressively from the surface of the pill to the point 5 where the maximum tension is reached, the maximum tension being maintained constant during the remainder 10 of the winding.

It will be understood that the balls wound in accordance with my invention are covered with the usual gutta percha cover 7 in the usual manner.

It will also be understood that the invention 15 may be carried out, winding either a single strand or a plurality of strands of rubber.

It will be understood that the invention may be variously modified and embodied within the 20 scope of the subjoined claims.

I claim as my invention:

1. A golf ball having a substantial portion of its volume formed of successive convolutions of rubber strand in a state of tension progressively increasing from the inner of said convolutions to 25 the outer of said convolutions, and another substantial portion of its volume formed of successive convolutions of rubber strand in a state of substantially equal tension.

2. A golf ball having a first substantial portion 30 of its volume formed of successive convolutions of rubber strand in a state of tension that progressively increases from the inner of said convolutions to the outer of said convolutions, and a second substantial portion of its volume formed 35 of successive convolutions of rubber strand in a state of substantially equal tension greater than the maximum tension existing in said first portion, and said second portion forming the outside layers of the wound portion of the ball. 40

3. A golf ball consisting of a wound portion and a cover and having its entire volume, except the cover, formed of successive convolutions of rubber strand in a state of tension, the tension of the strand forming the respective convolutions of one substantial portion of said ball progressively increasing from the inner of said convolutions to the outer of said convolutions, and the tension of the strand forming the respective convolutions of another substantial portion of 50 said ball being substantially equal.

4. A golf ball consisting of a wound portion and a cover and having its entire volume, except the cover, formed of successive convolutions of rubber strand in a state of tension, the tension 55

of the strand forming the convolutions of a substantial portion of said ball progressively increasing from the inner of said convolutions to the outer of said convolutions, and the tension of the strand forming the convolutions of another substantial portion of said ball being substantially equal, the portion having substantially

equal tension forming the outside layer of the wound portion of the ball, and the said tension being greater than the maximum tension of the strand forming the convolutions of the first portion.

BORIS BOGOSLOWSKY.
